UNITED STATES PATENT OFFICE.

ARCHIBALD JOHNSTON, OF BETHLEHEM, PENNSYLVANIA, ASSIGNOR TO BETHLEHEM STEEL COMPANY, OF BETHLEHEM, PENNSYLVANIA, A CORPORATION OF PENNSYLVANIA.

HEAT-REGULATING DEVICE.

No. 824,723.

Specification of Letters Patent.

Patented July 3, 1906.

Application filed August 18, 1904. Serial No. 221,269.

To all whom it may concern:

Be it known that I, ARCHIBALD JOHNSTON, a citizen of the United States, residing at Bethlehem, in the county of Northampton, State of Pennsylvania, have invented certain new and useful Improvements in Heat-Regulating Devices, of which the following is a specification.

This invention relates to heat-regulating devices for furnaces, and especially for that class of furnaces known as "regenerative" furnaces, and has for its object the provision of improved means for regulating the heat.

The invention will be described in connection with the accompanying drawings, of which

Figure 1 is a longitudinal vertical section on line *a b* of Fig. 3. Fig. 2 is a horizontal section on the line *c d* of Fig. 1 looking in the direction of the arrow. Fig. 3 is a transverse vertical section on the line *e f* of Fig. 1.

The furnace, which is suitably supported on a foundation, comprises a furnace-chamber A, along each side of which extends the longitudinal regenerating gas-chamber B and the regenerating air-chamber C. The regenerating gas-chambers may be connected by any suitable means, as flues D, with a source of gas, while the air-chambers may be connected by flues E with a source of air. The connections of the air and gas flues with the sources of air and gas may be controlled by the usual reversing-valves, whereby when the flues D and E, leading to one side of the furnace-chamber, are in connection with the sources the flues leading to the other side of the chamber are connected with the stack F. The result of this arrangement, as is well known, is that the air and gas after passing through the regenerating-chambers upon one side are discharged into the furnace-chamber upon that side, whereupon having been previously heated in the regenerating-chambers they combine and in their passage through the furnace-chamber heat the contents thereof. The gases then pass out of the other side of the furnace-chamber into the regenerating-chambers, in which heat remaining in the products of combustion is extracted and retained. The products then pass on to the stack. At regular intervals the reversing-valves above referred to are thrown, so that the flow of air and gas

through the furnace is reversed, and thereby the heat which has been stored in a regenerative chamber by the gases of combustion during one period of operation is absorbed by the gases to be burned in a succeeding period. The apparatus thus far described is well known, and it is thought unnecessary to describe it in further detail. Hitherto, however, the means for regulating the heating of material within the furnace-chamber have been inferior. According to the present invention means are provided whereby all the material within the furnace may be heated uniformly regardless of whether the bodies to be heated are of the same or different sizes and also whereby the material may be heated without causing it to become oxidized. This is accomplished by providing means whereby the heating fluid, which in the present instance is that produced by the combustion of gas and air, may be caused to change its path through the furnace-chamber and with relation to the objects or material to be heated. This may be accomplished, as shown in the accompanying drawings, by providing a plurality of entrance-ports 1 and 2 for the gas conveyed from the regenerating-chamber B by the passage 3. Corresponding to each of the ports 1 and 2 for the gas are ports 4 and 5 for air, which is conveyed from the regenerating-chamber C by passages 6 and 7. In the present instance the ports 5 and 2 have a common inlet 20. In most forms of regenerative furnaces and in that shown the material to be heated will be placed upon the floor of the furnace. For this reason air and gas ports are located at different distances from the floor, so that the heating fluid may be made to pass either through the lower portion of the furnace-chamber, and thus into contact with or close to the material to be heated, or through the upper portion of the furnace-chamber and out of contact with the material below the current of gases, so that the heating of the latter is accomplished by radiation. In the latter case oxidation is prevented, and thereby the formation of scale on the surface of the heated material is avoided. The amount and direction of the heating fluid through either the upper or lower ports may be effected by means of valves 8 and 9, controlling the gas-passage, and valves 10, 11,

12, and 13, controlling the air-passages. The valves 9, 12, and 13 are located between the upper and lower ports, while the valves 8, 10, and 12 are located below the lower ports. It will be obvious that if valves 8, 10, and 11 be opened while valves 9, 12, and 13 are closed the heating fluid will be directed through the lower ports 1 and 4 and along the floor of the furnace-chamber. If now the valves 9, 12, and 13 be opened, the gas and air will flow through the upper ports and across the upper part of the furnace-chamber, taking a direct upward course instead of passing through the lateral ports 1 and 4. The air and gas supply is regulated in quantity by the lower valves 8, 10, and 11, and by means of the upper valves 9, 12, and 13 the air and gas is directed to the upper or lower outlets, or both, as may be desired.

The description of the flues, valves, and ports has been made with reference to one side of the furnace only; but since the two sides are alike this description applies equally to each.

The flues, valves, and ports described upon one side of the furnace-chamber, with a similar arrangement upon the opposite side of the chamber, constitute a section. The furnace comprises several of these sections longitudinally arranged. (See Figs. 2 and 3.) Since each of the sections has its own valves, the stream of heating fluid through it may be regulated independently of the other sections. In this way a plurality of independently-regulable streams of heating fluid are obtained. The stream in one section may be caused to flow along the floor, while the streams in any or all of the other sections may be directed near the ceiling of the chamber. It will thus be seen that by properly adjusting the valves of the various sections the heat may be varied in the different sections. In this way the heat can be varied both vertically and longitudinally of the furnace to suit the size or nature of material heated.

While I have illustrated my invention in what I consider its best application, it may have other embodiments, and I do not, therefore, wish to be limited to the construction shown.

What I claim is—

1. In a regenerative furnace, the combination with a furnace-chamber, of means for supplying a plurality of streams of heating fluid to said chamber, and means for changing the path of each of said streams inde-

pendently of the others, for the purpose set forth.

2. In a regenerative furnace, the combination with a furnace-chamber, of means for supplying a longitudinally-arranged series of streams of heating fluid and means for changing the path of each of said streams independently of the others, for the purpose set forth.

3. In a regenerative furnace, the combination with a furnace-chamber, of means for supplying a longitudinally-arranged series of streams of heating fluid, and means whereby each of said streams of heating fluid may be directed into said chamber at different elevations independently of the others, for the purpose set forth.

4. In a regenerative furnace, the combination with the furnace-chamber and air and gas heating chambers, of a plurality of passages leading from the air and gas heating chambers to each side of the furnace-chamber, means for regulating the flow of air and gas through said passages, outlets for said passages at different elevations, and means for directing the air and gas either to the upper or lower outlets, whereby different amounts of heat may be simultaneously supplied to different parts of said furnace-chamber.

5. A regenerative furnace divided into a plurality of sections, each of said sections having at one side a plurality of gas-ports at different elevations and corresponding air-ports, similar ports upon the opposite side of the furnace, and controlling means for the ports upon each side of the furnace whereby the air and gas may be directed to ports in either section and at either elevation.

6. The combination with a single furnace-chamber, of a plurality of ports at different elevations on each side of said chamber, means for supplying heating fluid to either port on either side of said chamber, each of said ports being also adapted for the exit of gases of combustion, whereby the heating fluid may be directed to different elevations in the chamber and the products of combustion withdrawn at different elevations, for the purpose set forth.

In testimony whereof I have signed my name to this specification in the presence of two subscribing witnesses.

ARCHIBALD JOHNSTON.
